TYPE BAR SEGMENT AND ANVIL

Herbert C. Shepard, Frankfort, N. Y., assignor to
Remington Rand Inc., New York, N. Y., a corporation of Delaware

Application February 12, 1934, Serial No. 710,953

5 Claims. (Cl. 197—183)

My invention relates to typewriting and like machines and more particularly to type bar segments and anvils.

It has been customary heretofore to make the usual slotted type bar segment of cast iron, the use of cast iron being preferable to facilitate manufacture and to readily provide proper bearing surfaces for the heels or fulcrumed ends of the type bars. In the manufacture of such cast iron segments it has been customary to form integral therewith an anvil that is located near the fulcrumed ends of the type bars, so that each type bar in its approach to the printing position contacts with the anvil in such a manner that the type bar is arrested just before the face of a type thereon strikes the platen, the impression being made on the platen, or the paper carried thereby, by an overthrow or spring of the free end portion of the type bar which extends beyond the point where it is arrested by the anvil. In order to provide proper effective imprints from the type bars the contact face of the anvil should be maintained in a very exact relationship to the type bar fulcrum wire and the platen. In the usual construction the effectiveness of this cast iron anvil is of comparatively short duration due to the fact that the hard steel type bars soon wear or cut into the anvil to such an extent as to seriously impair the printing.

One of the main objects of my invention is to overcome these difficulties and provide means for effectively securing a hardened tool steel anvil to a cast iron segment and for bringing the contact face of the anvil into proper relationship with the pivot wire for the type bars.

To the above and other ends which will hereinafter appear, my invention consists in the features of construction, arrangements of parts and combinations of devices set forth in the following description and particularly pointed out in the accompanying claims.

In the accompanying drawing wherein like reference characters indicate corresponding parts in the different views—

Fig. 1 is a front view of a type bar segment and anvil constructed in accordance with the present invention, together with some of the associated parts.

Fig. 2 is an enlarged, detail, vertical, sectional view of the same showing a type bar in contact with the anvil.

Fig. 3 is a perspective view of an anvil constructed in accordance with my invention but shown detached.

Fig. 4 is an enlarged, detail, fragmentary, trans-

verse sectional view of the segment and anvil taken on the line 4—4 of Fig. 1 and looking in the direction of the arrows at said line.

Fig. 5 is a like view of the same showing one of the screws which secures the anvil in place as it appears after the outer head has been twisted off and before the projecting portion of the inner head has been ground down.

Fig. 6 is a corresponding view showing one of said screws as it appears when the anvil has been secured in place but before the outer head has been twisted off.

In the accompanying drawing 10 represents the usual cast iron segment but which in the present instance is devoid of the integral anvil ordinarily provided thereon. This segment is provided with the usual seat or recess 11 in which a segmental pivot wire 12 for the type bars 13 is received, the heel of each of said type bars operating in a slot 14 in the lower edge portion of the segment and being guided by the side walls thereof. A segmental anvil 15 which is preferably made of hardened tool steel is provided with counter-sunk openings 16 therein. These openings, when the anvil is in position for use, register with tapped openings 17 that extend through the body of the segment. The counter-sunk portions of the openings 16 are at front of the anvil to receive correspondingly shaped inclined surfaces of the inner heads 18 of screws 19 which are preferably made of hardened tool steel. Each screw has a double head thereon comprising the inner head 18 and an outer head 20, the latter being provided with a slot 21 to receive the end of a screw driver. A reduced portion 22 intervenes between the inner and outer heads of each screw to form a weakened portion that enables the outer head 20 to be readily twisted off the inner head 18, leaving the screw in some such condition as that indicated in Fig. 5. When each screw 19 has been threaded home to firmly secure the anvil 15 to the segment, as shown in Fig. 6, the outer head of said screw will be twisted off, leaving the parts somewhat as shown in Fig. 5.

The segment is then set up and the broken off protruding ends of the screws 19 are ground down flush with the contact face of the anvil and such contact face and the heads 18 are ground down an appropriate amount to accord with the position of the pivot wire 12, in order that each type bar will be arrested by the anvil in proper position to afford an accurate and proper imprint by an overthrow of the free end of each type bar in its impact against the platen 23 or the paper thereon.

By grinding down the contact face of the anvil and the heads 18 in the manner described a hard, continuous, unbroken, exact, substantially wear-proof contact surface is provided on the anvil 5 for the type bars to strike against.

By fixedly attaching the hardened tool steel anvil to the face of the cast iron segment in the manner and by the means hereinbefore pointed out, the construction can be readily and cheaply 10 produced, facilitating an accurate manufacture of the parts to attain the results pointed out.

Changes in the construction hereinbefore described may be made without departing from my invention as it is defined in the accompanying 15 claims.

What I claim as new and desire to secure by Letters Patent is:

1. A type bar segment and anvil for typewriting and like machines comprising a slotted type 20 bar segment of cast iron having a seat therein for the type bar pivot wire and tapped openings that extend through said segment, and a hardened tool steel anvil firmly secured throughout its extent to the front face of the segment by screws 25 of hardened tool steel that are received in said tapped openings, the front contact face of said anvil and any extending portions of the screws being ground down an appropriate amount to accord with the position of the type bar pivot wire 30 in said seat.

2. A type bar segment and anvil for typewriting and like machines comprising a slotted type bar segment of cast iron having a seat therein for the type bar pivot wire and tapped openings 35 that extend through said segment, and a hardened tool steel anvil firmly secured to the front face of the segment by headed screws of hardened tool steel that are received in said tapped openings, the heads of the screws being located at the 40 front of the anvil, the front contact face of the anvil and the heads of the screws being ground down an appropriate amount to accord with the position of the type bar pivot wire in said seat.

3. A type bar segment and anvil for typewriting and like machines comprising a slotted type 45 bar segment of cast iron having a seat therein for the type bar pivot wire and tapped openings that extend through said segment, a hardened tool steel anvil having counter-sunk openings in 50 the front face thereof, and hardened tool steel screws that are received in said tapped openings and firmly secure the anvil to the segment, each of said screws having a double head with an in-

tervening weakened portion that permits the outer section of the head to be twisted off the inner section thereof after the screw is threaded home, the inner section of each head fitting in the companion counter-sunk opening in the anvil and 5 having the projecting portion thereof ground down flush with the contact face of the anvil after the outer section of the head has been removed.

4. A type bar segment and anvil for typewriting and like machines comprising a slotted type bar segment of cast iron having a seat therein for the type bar pivot wire and tapped openings that extend through said segment, a hardened tool steel segmental anvil against which the type 15 bars strike, said anvil having openings there-through for the passage of screws, each of said openings being counter-sunk in the front contact face of the anvil, and hardened tool steel screws received in said tapped openings and firmly se- 20 curing the anvil to the segment, each of said screws having a double head with an intervening weakened portion that permits the outer section of the head to be twisted off the inner section after the screw is threaded home, the projecting 25 portions of the inner heads of the screws being ground down flush with the contact face of the anvil.

5. A type bar segment and anvil for typewriting and like machines comprising a slotted type 30 bar segment of cast iron having a seat therein for the type bar pivot wire and tapped openings that extend through said segment, a hardened tool steel segmental anvil against which the type bars strike, said anvil having openings there- 35 through for the passage of screws, each of said openings being counter-sunk in the front contact face of the anvil, and screws received in said tapped openings and firmly securing the anvil to the segment, each of said screws being of hardened 40 tool steel and having a double head with an in- tervening weakened portion that permits the outer section of the head to be twisted off the inner section after the screw is threaded home, the inner section of each head fitting in the com- 45 panion counter-sunk opening and the contact face of the anvil and the broken projecting ends of the inner heads of the screws being ground down an appropriate amount to accord with the position of the pivot wire in said seat after the 50 outer sections of the heads have been removed.

HERBERT C. SHEPARD.
